UNITED STATES PATENT OFFICE

2,580,185

TRAFFIC BEARING SLAB

Harold Nagin, Pittsburgh, Pa., assignor to Reliance Steel Products Company, McKeesport, Pa., a corporation of Pennsylvania

Application May 14, 1947, Serial No. 747,881

3 Claims. (Cl. 94—8)

1

This invention is for a concrete slab for use as a surface for roadways, bridges and other traffic bearing structures, and is especially applicable to constructions of this kind employing metal gratings.

Metal gratings are commonly used in bridge and road surfaces for both structural purposes and traction purposes. Generally they provide longitudinal and transverse bars welded together and the spaces between are filled with concrete, the concrete being initially flush with the grating. The surface of the slab so made presents the appearance of square or rectangular cells filled with concrete.

An objection to such slabs is that as traffic passes over the surface, the concrete wears away, leaving cupped surfaces. If the grating is made with large cells, the cupping may become quite deep, and if the cells are too small, the tires ride principally on the metal and skidding is less effectively prevented.

The present invention provides a slab in which the wear of the concrete is minimized, and in conjunction with grating, it enables large "cells" to be used without excessive cupping. The invention may in addition provide additional reinforcement to the slab. My invention contemplates the use of elements in the slab which extend vertically and provide metal columns of small section or area which are flush with the original surface of the concrete. They are so placed that they take part of the load on the road surface, and hence retard wear and prevent the cupping from becoming too deep and at the same time do not provide any such continuity of metal as to cause the wheels to "track" and tend to retard rather than increase skidding.

My invention may be readily understood by reference to the accompanying drawings in which:

Fig. 1 is a plan view of a grating, partly filled with concrete and partly unfilled;

Fig. 2 is a transverse section through one form of slab embodying my invention;

Fig. 3 is a longitudinal section;

Fig. 4 is a plan view of another form of slab; 45 and

Fig. 5 is a longitudinal section through another form of slab.

Referring first to Figs. 1 to 3 of the drawing, a slab is made up from a conventional form of grating which, for example, has longitudinally extending parallel bearer bars 2 with cross bars 3 connecting the same, the bars 2 being the full depth of the grating while the bars 3 pass through the webs of the sections 2 and have their top edges

5 flush with the tops of the sections 2. There are transverse load distributing bars in the lower part of the structure, these being designated 4.

The square areas defined by the intersecting bars 2 and 3 are designated 5, and the concrete 6 is filled into the grating and is initially flush with the tops of the members 2 and 3.

According to the present invention one or more upright rods 7 are placed in each cell, preferably 10 at the center. This may conveniently be done by welding the short vertical sections of rod 7 to a horizontal bar 8 which is then lightly welded into the grating before the concrete is poured. Preferably the bar 8 and the rods 7 are so set as 15 to bring one of the upright bars 7 to about the center of each cell. The tops of the bars 7 are flush with the top of the grating.

The concrete is poured into the structure in 20 the usual manner. The rods might be short lengths, but preferably they extend through substantially the full thickness of the slab and thereby provide vertical or "stirrup" type reinforcements.

It will be seen that while the grating provides 25 all of the usual advantages in the traffic bearing slab, the cells may be relatively large and yet the pins or uprights 7 will prevent the tires from sinking too deeply into the concrete or, in other words, the pins limit the "cupping action" of the tires in hollowing out the concrete. At the same time the weight of the slab and the labor cost is much less than it would be if relatively smaller cells were provided. In addition, while the posts or pins limit the wear, they do not objectionably increase the metal surface, and being discontinuous, they retard skidding, whereas an increase in the number of bearing bars and transverse bars, resulting in smaller cells, would substantially increase the cost, the weight, the labor and the continuity of the metal load bearing surfaces. The rods 7 are of relatively small cross section, being of the order of perhaps a $\frac{3}{4}$ " round.

In Fig. 4 I have shown a concrete slab 10 employing no grating, but armored only with the vertical rods 11 which are attached to a mesh reinforcing structure 12. Here again the rods may extend substantially through the slab, or only part way through. They are, of course, closer together where they provide the only protection. While they are shown in rows, obviously they may be staggered. The only necessity is that they be sufficiently close and numerous to avoid excessive cupping of the concrete as for example from three to four inches on centers.

In Fig. 5 the slab is armored by the use of individually positioned elements 15 having an upright post portion 15a and a horizontal thrust distributing arm portion 15b. These may be used with the grating in lieu of the arrangement shown in Fig. 1, and with or without being attached to any frame or reinforcement.

All forms of the invention provide wear resisting surfaces in a concrete slab of small exposed area capable of providing the total protection to the wearing of the concrete or important secondary protection, the grating being the primary protection.

While I have shown and described certain embodiments of my invention, it will be understood that these are illustrative and that various changes and modifications may be made therein.

I claim:

1. In a traffic bearing slab, a grating structure comprising intersecting metal reinforcing bars arranged to provide substantially rectangular spaces therebetween, a traffic bearing material filling said spaces, said bars and material having upper surfaces flush with each other to provide a traffic bearing surface, and means for minimizing cupping of the traffic bearing material in said spaces due to traffic passing thereover comprising a metal post arranged vertically in each of said spaces, each of said posts having a surface at its upper end spaced from said reinforcing bars and flush with and forming part of said traffic bearing surface.

2. In a traffic bearing slab, a grating structure comprising intersecting metal reinforcing bars arranged to provide substantially rectangular spaces therebetween, a traffic bearing material filling said spaces, said bars and material having upper surfaces flush with each other to provide a traffic bearing surface, and means for minimizing cupping of the traffic bearing material in said spaces due to traffic passing thereover comprising a metal reinforcing element embedded in the material filling each of said spaces

and providing a surface spaced from said intersecting bars and is flush with and forms part of said traffic bearing surface, the provision of said reinforcing element surfaces enabling a wider spacing of said intersecting bars without noticeable cupping than otherwise possible.

3. In a reinforced concrete slab, a grating structure comprising intersecting metal bars positioned edgewise and defining cell areas therebetween, each of said areas having a filling of concrete therein to a level flush with the upper edges of said bars, the edges of said bars and said concrete cooperating to form a traffic bearing surface, said bars being spaced from each other a distance such that movement of rubber-tired vehicles over the surface of the concrete therebetween would otherwise be effective to cause an objectionable cupping action by wearing away the concrete in said cell areas to a level below the upper edges of the bars, and means for preventing said cupping action consisting of a metal reinforcing element embedded substantially centrally of each of said cell areas and extending vertically downwardly from said bearing surface, the upper ends of said elements being flush with and forming part of said bearing surface.

HAROLD NAGIN.
